GUTTER CIRCLE AND METHOD OF MAKING
SAMEMax Rachlin, Flushing, N. Y.; Helen Pollock and
Eva Rachlin, executrices of said Max Rachlin,
deceased

Application April 4, 1947, Serial No. 739,429

6 Claims. (Cl. 248—48.2)

1

This invention relates to a gutter circle and is more particularly directed to a circle which has its major portion of channel or U-shaped section, this portion merging into an attaching portion which is substantially flat.

It is one object of the invention to provide a gutter circle made from a minimum amount of metal and yet one which possesses sufficient strength to withstand extremely heavy loads imposed upon the supported gutter.

It is a particular object of the invention to provide an extremely strong gutter circle which is made with a minimum waste of material, the only material being wasted being that wasted by trimming relatively small areas in order to improve the appearance of the finished circle.

It is a further object of the invention to provide a gutter circle with a bead retaining clip, the construction being such that the clip can be inserted in slots in the circle and retained therein by a simple manipulative step.

It is another particular object of the invention to provide a channel shaped circle with flanges extending from the base of the channel, these flanges being parallel throughout their lengths and then merging into an attaching portion so as to form sharply defined right angles between the plane of the attaching portion and the parallel planes of the flanges.

Another detailed object of the invention is to provide a substantially flat attaching portion of a gutter circle with a raised central portion, thus providing what may be termed a corrugation which strengthens the attaching portion and thus resists bending stresses occasioned by overloading of the gutter. It is well-known that roof gutters frequently are subjected to overloading by ice and also by workmen such as painters or the like, standing in the gutter or placing ladders therein. The channel shape of the major portion of the gutter circle and the corrugation of the attaching portion are specifically designed to resist such overloading.

To the accomplishment of the foregoing and related ends, said invention, then, consists of the means hereinafter fully described and particularly pointed out in the claims.

The annexed drawing and the following description set forth in detail one method and one product exemplifying my invention, such disclosed procedure and product constituting, however, but one of various applications of the principle of my invention.

In said annexed drawing:

Fig. 1 is a perspective view of the completed gutter circle,

2

Fig. 2 is a plan view taken from above of the blank after the same has been severed from the stock sheet.

Fig. 3 is a side elevation of the blank shown in Fig. 2,

Fig. 4 is a rear elevation of the blank after the second forming step,

Fig. 5 is a side elevation of the blank shown in Fig. 4,

Fig. 6 is a rear elevation similar to Fig. 4 but after the next forming operation,

Fig. 7 is a side elevation of the blank shown in Fig. 6,

Fig. 8 is a partial side elevation similar to Fig. 7 but after the final forming step,

Fig. 9 is a broken perspective view of the end portion of a modification,

Fig. 10 is a broken perspective view of the end portion of another modification.

Referring now to the drawings and more particularly to Fig. 1, it will be seen that the completed gutter circle comprises a gutter supporting portion which is channel shaped or U-shaped in cross section. This channel shaped part comprises the parallel flanges 1 and 2 joined by the base 3, this base being designed to receive and contact the gutter. Flanges 1 and 2 merge into the spaced portions 4 and 5 which are provided with perforations 12 so as to receive securing means such as nails, screws, bolts and the like. Slots 8 and 9, shown in Figs. 2, 5 and 7, are provided to receive the clip 13. The clip in turn is retained in place by bending the outer portions 16 and 17 of the flanges 1 and 2 downwardly so that each of the slots is restricted in width at its outermost portion. The base 3 of the channel shaped section merges into the central portion 16a which lies between the attaching ears 4 and 5 and the portion 16a continues upwardly and is bent into the form of a retaining lip 11 which engages the upper inner edge of the gutter.

The blank A shown in Figs. 2 and 3 is cut from a sheet of metal (not shown), the sheet being approximately as wide as the length of the blank. During the initial forming step which may be cutting, sawing, stamping or otherwise, the lip 11 is bent slightly out of the plane of the blank A and the blank is trimmed to provide the curved end portion 10, the corresponding edges 6 and 7, as well as the slots 8 and 9, and the curved end portion adjacent the lip 11. All of this is done in one operation, thus saving time and labor and providing a blank formed with a minimum amount of waste. It may be stated that the edges 6 and 7 at the right hand end of the blank A,

as seen in Fig. 2, are results of the trimming operation, this trimming being done solely to enhance the appearance of the gutter circle in its final condition.

After the blank A has been formed by severing from a sheet of stock, it is then converted into a channel shaped member as shown in Figs. 4 and 5. Here it will be noted that the flanges 1 and 2 are co-extensive and parallel and extend throughout the length of the circle to form the intermediate product or blank B. (See Figs. 4 and 5.)

The blank B is then subjected to a further forming operation in which the attaching portion is formed, this portion comprising spaced ears 4 and 5 separated by the central area 16. It is also to be noted that in this step, the area 16a lies in a plane slightly out of the plane of the ears 4 and 5, this resulting in what may be termed a corrugation which in turn lends considerable strength to the attaching portion and prevents the same from bending. This is a very important feature of my invention.

The clip 13 is next inserted in slots 8 and 9, after which the outer portions 16-17 of the circle are bent toward flanges 1 and 2 respectively so that the slots decrease in width, thus retaining the clip in place. This bending may be performed by exerting force against the outer base portion 3 in the direction of the arrow Fig. 8, so that the small triangular portions 16 and 17 are bent about the clip 13 as shown in Fig. 8.

Referring now to the clip, it will be noticed that this comprises a wire-like member having a longitudinal portion 13 which is considerably longer than the distance between the flanges 1 and 2. This relatively longitudinal portion 13 is provided at its ends with hook members 14 and 15. The length of the clip, or stated in other words, the distance between the hooks 14 and 15 is quite important since this permits the use of a single size of gutter circle with several different sizes of gutter. This last result is due to the fact that this clip is of resilient material and also because of the spacing of the hooks so that the hook 14, for example, may be slipped over the bead of a gutter, after which the hook 15 can be slipped over the side according to the dimensions of the gutter circle.

Referring now to Fig. 9, it will be seen that the parallel flanges 1a-2a are bent along a line 20 and forced toward each other so as to abut in the region between the line 20 and the lower outer edge of the circle. It is not deemed necessary to show a complete circle since the end portion only is modified, and the portion of the circle not shown in Fig. 9 corresponds exactly with the circle shown in Fig. 1. The bending of the flanges and forcing the same together imparts strength to the outermost portion of the gutter circle, which is the point of greatest stress. This modification is provided with a slot 21 adapted to receive a clip as shown in Fig. 1.

Referring now to the modification in Fig. 10, this view is similar to Fig. 9 in that the remainder of the circle, which is not shown, corresponds to a like portion of the circle shown in Fig. 1. In this modification the blank need not be trimmed to provide the curved edges 6 and 7 as shown in Fig. 2 and consequently the blank will resemble a rectangle except for the curved portions adjacent the attaching apertures 12. Instead of trimming, the outermost portions 22 and 23 of flanges 2b and 1b respectively are overlapped to form a closed clip receiving pocket.

The clip 24 is easily inserted in the pocket formed by the overlapping portions 22 and 23 and after insertion, the ends 25 and 26 contact the exterior portions of flanges 1b and 2b. The opposite end of the clip 24, that is the rounded portion, obviously is adapted to engage the bead of a gutter. This modification differs from the others in that waste is reduced to a positive minimum, and the clip engages the flanges of the gutter circle rather than a slot in such flanges.

From the foregoing it will be seen that I have provided a gutter circle which can be made with an extremely small amount of waste and it will be further noted that I can form my gutter circle with a relatively few simple steps. In addition, it will be noted that I have provided a clip which is permanently secured to the circle and one which can be used with various sizes of gutters. In addition, the clip can be easily attached to a gutter circle bead, as distinguished from clips having hook portions relatively closely spaced, thus requiring a different size of gutter with each size of gutter circle.

In conclusion, it will be seen that I have provided a strong gutter circle since the gutter supporting portion is of channel shape throughout its length and it merges into a reinforced attaching portion, the parallel flanges 1 and 2 of the channel shaped portion extending at sharp right angles to the attaching portion.

Other forms may be employed embodying the features of my invention instead of the one here explained, change being made in the form or construction, provided the elements stated by any of the following claims or the equivalent of such stated elements be employed, whether produced by my preferred method or by others embodying steps equivalent to those stated in the following claims.

40 I therefore particularly point out and distinctly claim as my invention:

1. A method of making a gutter circle which comprises the steps of providing a flat sheet of metal, then forming a substantially flat, substantially rectangular blank, then bending said blank into an arcuate channel shaped member with parallel flanges in one step, then bending said flanges at one end of the channel shaped member to form an attaching portion that extends completely in a plane at right angles to the plane of each of said flanges.

2. A method of making a gutter circle which comprises the steps of providing a flat sheet of metal, then forming a substantially rectangular blank, simultaneously with said forming operation trimming one of the ends of said blank and providing slots in said one end of the blank, then bending said blank into an arcuate channel shaped member with parallel flanges in one step, then bending said flanges at one end of the channel shaped member to form an attaching portion that extends completely in a plane at right angles to the plane of each of said flanges.

3. A method of making a gutter circle which comprises the steps of providing a flat sheet of metal, then forming a substantially rectangular blank, simultaneously with said forming operation providing slots in one end of said blank, then bending said blank into an arcuate channel shaped member with parallel flanges, then bending said flanges at one end of the channel shaped member to form an attaching portion that extends completely in a plane at right angles to the plane of each of said flanges, and then in-

serting a clip in said slots and finally securing said clip in said slots.

4. A method of making a gutter circle which comprises the steps of providing a flat sheet of metal, then forming a substantially rectangular blank, simultaneously with said forming operation providing slots in one end of said blank, then bending said blank into an arcuate channel shaped member with parallel flanges, then bending said flanges at the other end of the channel shaped member to form an attaching portion that extends in a plane at right angles to the plane of each of said flanges, and then inserting a clip in said slots, and finally bending said one end to decrease the width of said slots beyond 15 said clip whereby said clip is retained in place.

5. A method of making a gutter circle which comprises the steps of providing a flat sheet of metal, then forming a substantially rectangular blank, simultaneously with said forming operation trimming one of the ends of said blank and providing slots in said one end of the blank, then bending said blank into an arcuate channel shaped member with parallel flanges in one step, then bending said flanges at one end of the channel shaped member to form an attaching portion that extends completely in a plane at right angles to the plane of each of said flanges, then pressing said flanges together at the other end of said channel shaped member to strengthen the outer- 25 most part of said circle. 30

6. A gutter circle comprising a channel shaped, arcuate, gutter supporting portion, an attaching portion at one end of said arcuate portion, the gutter supporting portion having flanges that are parallel from said attaching portion throughout the major portion of their extent, said flanges merging together and contacting each other at the end of said gutter supporting portion opposite to said attaching portion, the planes of the flanges and the plane of the attaching portion being disposed at right angles and the juncture of such planes lying along parallel straight lines.
